ELECTRIC HIGHWAY EMERGENCY BEACON

John K. Lawlor, 2080 E. Grand,
Escondido, Calif. 92027

Filed Nov. 7, 1972, Ser. No. 304,364

Term of patent 14 years

Int. Cl. D29—02

U.S. Cl. D10—114

FIG. 1.

FIG. 2.

FIG. 1 is a side perspective view of an electric highway emergency beacon showing my new design, the opposite side being a mirror image.

FIG. 2 is a bottom view thereof.

I claim:

The ornamental design for electric highway emergency beacon, substantially as shown and described.
